(57) **CLAIM**

The ornamental design for fishing reel, as shown and described.

DESCRIPTION

FIG. 1 is a first perspective view of a fishing reel in accordance with our new design;

FIG. 2 is a second perspective view of the fishing reel illustrated in FIG. 1;

FIG. 3 is a side elevational view of the fishing reel illustrated in FIG. 1;

FIG. 4 is an opposite side elevational view of the fishing reel illustrated in FIG. 1;

FIG. 5 is a top plan view of the fishing reel illustrated in FIG. 1;

FIG. 6 is a bottom plan view of the fishing reel illustrated in FIG. 1;

FIG. 7 is a rear elevational view of the fishing reel illustrated in FIG. 1;

FIG. 8 is a front elevational view of the fishing reel illustrated in FIG. 1; and

FIG. 9 is another side elevational view, similar to FIG. 3, of the fishing reel illustrated in FIG. 1, but with the rotor rotated ninety degrees by operation of the handle.
